UNITED STATES PATENT OFFICE.

ROY LABBE, OF BALTIMORE, MARYLAND.

AUTOMATIC SWITCH.

1,413,740.

Specification of Letters Patent. Patented Apr. 25, 1922.

Application filed June 11, 1921. Serial No. 476,811.

To all whom it may concern:

Be it known that I, ROY LABBE, a citizen of the United States, residing at Baltimore city, State of Maryland, have invented certain new and useful Improvements in Automatic Switches, of which the following is a specification.

This invention relates to electric switches, and its object is to provide a novel and improved switch mechanism for controlling a plurality of circuits.

The invention also has for its object to provide a novel and improved means for operating the switch.

Other objects and advantages of the invention will be pointed out in the detailed description hereinafter, and in order that the same may be better understood, reference is had to the accompanying drawings forming a part of this specification.

In the drawings—

Figure 1 is an elevation showing one side of the switch mechanism; Fig. 2 is an elevation showing the other side; Fig. 3 is a horizontal section on the line 3—3 of Fig. 1; Fig. 4 is a plan view of a pawl-releasing mechanism, and Fig. 5 is a section on the line 5—5 of Fig. 1.

Referring specifically to the drawings, 10 denotes a housing which encloses and supports the various elements of the switch mechanism, said housing being made of porcelain or other suitable non-conducting material.

35 On one of the walls of the housing is mounted a series of stationary switch-contact members 11 which are engageable by a movable switch plate or blade 12 having a sector-like shape, and pivotally supported, as shown at 13, to the housing wall. A torsion spring 14 engages the blade and tends to swing it in one direction. The contacts 11 are arranged in an arcuate curve having for its center the pivot 13 of the blade 12, 45 and they are spaced from each other so that when the blade is swung in their direction it comes in contact with the same in succession. The width of the blade 12 where it engages the contacts 11 is such that it may 50 engage the entire series of contacts.

The following means are provided for operating the switch blade or plate 12:

In a housing 15 carried by a bracket 16 on the housing 10, is slidably mounted a pawl-carrier 17 to the forward end of which is pivoted, as shown at 18, a pawl 19 adapted

to engage lugs or abutments 20 on the plate 12 corresponding in number and grouping to that of the contacts 11. The pawl 19 is designed to impart to the plate 12 a step-by-step swinging movement to bring it into engagement with the contacts 11, one after the other. A spring 21 attached to the carrier 17 and pressing against the pawl 19 yieldingly holds the latter in operative position, and allows it to slip over the lugs 20 on the return or circuit-breaking stroke of the plate 12.

Slidably connected to the rear end of the pawl-carrier 17 is a rod 22 which passes into a longitudinal recess 23 in said carrier and has in said recess a head 24. The rear end of the rod 22 is loosely connected to a side lug 25 on a slide block 26 seating in the housing 15. A spring 27 is coiled around the rod 22, between the lug 25 and the rear end of the carrier 17.

On the rear end of the block 26 is a stem 28 which projects from the housing 15 through a hole in the rear end wall thereof, 80 and is connected to one of the arms 29 of a bell-crank lever fulcrumed on the bracket 16, as shown at 30, and having its other arm 31 connected to a push-button 32.

The carrier 17 normally, or when retracted, seats in the housing 15 in an inclined position, and the block 26 is positioned between its rear portion and the opposite side wall of the housing. The carrier 17 also has a side shoulder 33 which abuts 90 against the inside of the housing end wall from which the carrier protrudes. The opposite side of the carrier 17 is engaged by a flat spring 34 which tends to hold the same pressed against the block 26, and with the shoulder 33 engaging the front wall of the housing 15. Fig. 3 shows the parts in their normal position.

When the push-button 32 is pressed in, the block 26, through the connections 28, 29 and 31, is made to slide forwardly, and as the lug 25 is carried by the block and carries the rod 22, said rod also moves forwardly in the direction of its length, so that the spring 27 is compressed between the advancing lug 25 and the rear end of the now stationary carrier 17. As the block 26 moves forwardly along the inclined side of the carrier 17, it pushes or presses the same laterally to free its shoulder 33 from the front 110 wall of the housing 15, and when the shoulder is thus freed, the carrier is unlocked so

that it is now given a quick forward or working stroke by the spring 27 which had been compressed in the mean time. The forward stroke of the carrier 17, through the engagement of the pawl 19 with one of the lugs 20 swing the plate 12 one step to engage one of the contacts 11.

The pawl 19 and its carrier 17 are retracted after each working stroke, and hence a means must be provided for locking the plate 12 after each advance to switch-closing position. This locking means is a pawl 35 which engages lugs or abutments 36 on the plate 12. After the plate 12 has been swung to switch-closing position as described, and locked by the pawl 35, the actuating means of the pawl 19 are retracted by a spring 37 connected to the lever arm 29.

The spring 37 is stretched when the button 32 is pushed in to operate the pawl 19, and when the button is released, said spring operates to restore the button to advanced or protruding position, and also to draw the block 26 back, which movement of the block, through the lug 25, rod 22 and head 24, retracts the carrier 17, and when the shoulder 33 comes opposite the edge of the front wall of the housing 15, the spring 34 rocks the carrier to engage the shoulder with said edge, whereupon the carrier is again locked in retracted position, as shown in Fig. 3. The carrier 17 has a projecting side finger 37' which works in a guide slot 38 in the side wall of the housing 15. The forward movement of the plate 12 is limited by a stop 39.

The pawl 35 which locks the plate 12 in circuit-closing position is pivoted to a support 40, as shown at 41. One side of the pawl 35 is engaged by a flat spring 42, and its other side is engageable by a longitudinally slidable trip rod 43. The support 40 is carried by the housing 15, and it has guides 44 for the trip rod 43.

The rear end of the trip rod 43 is connected by a link 45 to one arm 46 of a bell-crank lever having its other arm 47 connected to a push-button 48.

Assuming the pawl 35 to be engaging one of the lugs 36 to lock the plate 12, if the button 48 is now pushed in, the rod 43, through the connections 45, 46 and 47, is advanced to swing the pawl clear of the lug, whereupon the plate is released, and the spring 13 swings said plate back to circuit-breaking position.

In order to restore the tripping means of the pawl 35 to their normal position, after the plate 12 has returned to circuit-breaking position, there is pivoted to the housing 10, as shown at 49, a lever 50 carrying a link 51 which is connected to a lateral arm 52 on the rear end of the rod 43. The lever 50 has its lower free end positioned so as to be intercepted by a lug 53 on the plate 12 at

the end of its return stroke, and when said lug strikes the lever and swings the same, the link 51, through the arm 52, draws the rod 43 rearwardly to allow the pawl to again assume an operative position, and at the same time, the push-button 48 is advanced to its normal protruding position.

The switch mechanism is very efficient and reliable, and it is well adapted for controlling a group of lamps, as in a chandelier, where it is desirable at times to use only a portion of the lamps. Any number of lamps in the group, or the entire group may be turned on and off as desired. Each stroke of the button 32 cuts in one lamp, and one stroke of the button 48 cuts out all the lamps or any number which may have been cut in.

When the plate 12 has reached the limit of its circuit-closing position, a lug 54 on the end thereof comes opposite the pawl 19 to prevent further operation thereof. A stop 55 is also provided for limiting the swing of the plate 12 to circuit-opening position.

I claim:

1. An electric switch comprising a plurality of stationary contacts, a movable switch blade engageable with said contacts, means on the blade and a pawl engageable with said means for actuating the blade, a slidable carrier for the pawl, means for locking the carrier in retracted position, means for releasing the carrier, a spring for imparting a working stroke to the carrier after its release, means for locking the blade after each actuation, and means for operating said locking means to release the blade.

2. An electric switch comprising a plurality of stationary contacts, a movable switch blade engageable with said contacts, means on the blade and a pawl engageable with said means for actuating the blade, a slidable carrier for the pawl, means for locking the carrier in retracted position, means for releasing the carrier, a spring for imparting a working stroke to the carrier after its release, the aforesaid carrier-releasing means having means for placing the spring under compression, means for locking the blade after each actuation, and means for operating said locking means to release the blade.

3. An electric switch comprising a plurality of stationary contacts, a movable switch blade engageable with said contacts, means on the blade and a pawl engageable with said means for actuating the blade, a slidable carrier for the pawl, said carrier being also tiltable, means for locking the carrier in retracted position, a slidable member engageable with the carrier for tilting said carrier to release the same, actuating means for the slidable member, a spring for imparting a working stroke to the carrier

after its release, means for locking the blade after each actuation, and means for operating said locking means to release the blade.

- 5 4. An electric switch comprising a plurality of stationary contacts, a movable switch blade engageable with said contacts, means on the blade and a pawl engageable with said means for actuating the blade,
- 10 a slidable carrier for the pawl, said carrier being also tiltable, means for locking the carrier in retracted position, a slidable member engageable with the carrier for tilting said carrier to release the same, actuating
- 15 means for the slidable member, a spring for imparting a working stroke to the carrier after its release, the aforesaid slidable member also having means for placing the spring under compression, means for lock-
- 20 ing the blade after each actuation, and means for operating said locking means to release the blade.

- 5 5. An electric switch comprising a plurality of stationary contacts, a movable switch blade engageable with said contacts, means on the blade and a pawl engageable with said means for actuating the blade, a slidable carrier for the pawl, said carrier being also tiltable, means for locking the

carrier in retracted position, a slidable member engageable with the carrier for tilting said carrier to release the same, actuating means for the slidable member, an abutment on the slidable member, a rod carried by the abutment and having a connection with the carrier to slide relatively thereto in one direction and to retract the carrier when slid in the opposite direction, a spring between the carrier and the aforesaid abutment, means for locking the blade after each actuation, and means for operating said locking means to release the blade.

6. An electric switch comprising a plurality of stationary contacts, a movable switch blade engageable with said contacts, means for imparting a step-by-step movement to the blade to engage the contacts in succession, a pawl for locking the blade after each step, means for tripping the pawl to release the blade, means for returning the blade to circuit-breaking position when released, actuating means for the tripping means, and means operated by the blade on its stroke to circuit-breaking position for restoring the tripping means and its actuating means to inoperative position.

In testimony whereof I affix my signature.
ROY LABBE.
